CAR-DUMPING APPARATUS

Glenn W. Merritt, Bowerston, Ohio, assignor to
The Mining Safety Device Company, Bowers-
ton, Ohio, a corporation of Ohio

Application May 29, 1944, Serial No. 537,943

4 Claims. (Cl. 214—52)

1

This invention relates to car dumping apparatus. It has to do with that type of dump having a rotary cage in which a car, for instance a mine or railroad car, is received to be inverted for the purpose of discharging the contents.

Taken collectively, the improvements hereof are operable to control the turning over of the cage and relate particularly to the starting and stopping thereof.

One object of this invention is to provide a dump of the class described having a novel positive starter for the cage whose driving and driven elements will not jam in a dead center positional relation thereby preventing damage thereto together with novel means for checking the momentum of the cage near the end of the dumping cycle operable to bring the cage to a cushioned stop thereby reducing wear and tear on the equipment, particularly the rail aligning stop, and providing for more positive control over the stopping of the cage.

Other objects and advantageous features will be noted in the accompanying drawings and written description wherein like reference characters designate corresponding parts and wherein:

Figure 1 is an elevation of one end of the dump illustrating the novel positive starter.

Figure 2 is a detail view taken in the direction of arrows 2—2 of Figure 1.

Figure 3A is a detail of the positive starter showing the parts in another position.

Figure 3 is a detail of the positive starting lug.

Figure 4 is an end elevation, partly broken away of the opposite end of the dump illustrating the means for checking the momentum of the cage.

Figure 5 is a detail view taken in the direction of arrows 5—5 in Figure 4.

Figure 6 is a detail showing the cage as it approaches rail aligning position illustrating the means for checking the momentum of the cage at the beginning of the working stroke.

Figure 7 is a diagrammatic view in side elevation of a car dump of the class described.

With reference to Figure 7, 1 is the cylindrical rotary cage of a car dumper having thereon rails 2 for supporting a car 3 to be dumped. 4 is the approach track and 5 the receiving track over which full cars arrive at and empty cars leave the dump respectively.

The positive starter, illustrated in Figures 1, 2, 3 and 3a is located at the right hand end of the dump at the zone designated by A while the means for checking the momentum of the cage

2

illustrated in Figures 4 to 6, inclusive is located at the opposite end of the dump at the zone B.

Cages of this type are well-known in the art and the details of cage construction will be omitted except where necessary to properly describe the invention.

At one end of the cage is a ring rail 6, Figure 1 and a similar rail 7, Figure 4 is located at the opposite end. Said rails are supported on wheels 8, one of which as shown at 8a, is a driving wheel for revolving the cage. This wheel is mounted on a shaft 9 which is driven by gear 10, on shaft 9 and gear 11 on the shaft 12 of a two-speed motor 14 whose operation is preferably automatically controlled to rotate the cage slowly at the start to a point where the car starts to empty and then at a higher rate of speed in order to reduce the time for the complete dumping cycle. The cage is slowed down as it approaches rail aligning position by a limit switch 15 whose actuator 16 is engaged by a cam 17 rotating with one of the ring rails to energize the low speed windings of the motor. The motor circuit is de-energized by a stop switch 18 whose actuator 19 is arranged to be engaged just before the cage reaches rail aligning position by another cam 20 carried by the ring rail. Said motor may be provided with a magnetic brake to further assist in stopping the cage. The location and number of these switches 25 may be varied depending on the type and size of cage and other factors, the principal objective however being to complete the dumping cycle in a minimum interval of time while maintaining positive control over the movement of the cage and eliminating rough treatment thereof insofar as it is possible to do so by these provisions.

The positive starter, Figures 1, 2, 3 and 3a, may, for example, comprise a plurality of equidistantly spaced pins 21 mounted on the side of the drive 40 wheel 8a just below the periphery thereof, this general idea of positively starting a cage by means of such pins being disclosed in the patent to G. W. Merritt, number 1,735,778.

Pins 21, Figure 1 are adapted to engage a vertically disposed triangular shaped lug 22 pivotally attached to a thrust plate 23 located in a recess 24 between vertical webs 25 formed in the web of ring rail 6 to minimize the shear on the securing bolts 26. Said lug 22 is free to pivot on or with its horizontal, off center mounting pin 27 which is journaled in a boss 28 formed integral with the thrust plate, however upward movement, is limited by a horizontal stop 27' projecting from the thrust plate which engages a notch 30 formed in the upper edge of the lug. Downward move-

ment is limited by a stop member 31 projecting inwardly toward the ring rail from the side of lug 22 in such position as to engage the inside surface of the rail or any other suitably located surface and normally hold the lug in approximately the position shown in Figure 1 with one of the lug tips 32 projecting outwardly beyond the rail into the circular path of travel of the pins 21 about the axis of shaft 9.

In prior art structures, where pins similar to 10 pins 21 are rigidly mounted in the side of the drive wheel and ring rail and are arranged to travel in intersecting circular paths, it is possible for a driving pin and a driven pin to come together in a dead center relationship as the cage completes its revolution and returns to car receiving position. While in starting up the cage, there is no danger of such an event occurring, the drive may slip after the cage has been started and the pins have separated due to moisture or grease on the driving and driven surfaces or as the result of acceleration or deceleration of the drive wheel. Consequently, either one or both of the pins may be bent or broken off.

In the present construction, the tip 32 of the lug and the pins 21 on the drive wheel travel in intersecting circular paths. It is preferred that the tip project sufficiently far into the circular path of travel of the pins, see Figure 1, to maintain the starting thrust through several degrees of rotation of the cage in order to gain momentum before the drive is taken up solely by the drive wheel. As the cage completes its revolution and returns to car receiving position, see Figure 3A, it is possible for the tip 32 of the lug and one of the pins 21 to reach a dead center positional relationship, however the axis of rotation of the lug on the ring rail web is ahead of and above the point of contact and not on a line radial to the axis of the cage passing through said point of contact. Therefore, the lug tip will be displaced upwardly by the pin and, the bottom surface of the lug will ride harmlessly on top of the pin. As the pin moves on, the lug will drop down therebehind in position to be engaged by the next pin in succession upon subsequent starting up of the cage.

At the other end of the dump and on the opposite side of the cage is the novel means (sometimes called a retarder) for checking the momentum of the cage as it completes its revolution, see Figures 4, 5 and 6. Said means comprises, for example, a fluid displacement device having a cylinder 35 in which a valved piston 36 is disposed, mounted on one of the stationary frame members 37. The piston rod 38 is connected to a counterbalanced lever 39 pivoted at 40 on a standard 41. A pin 42 mounted on a bracket 43 attached to a cage part and rotatable with said cage is adapted to engage an inturned flange portion 44 of the lever 39, Figure 6, as the cage returns to upright position and raise the lever thereby forcing the piston downwardly in the cylinder and displacing the fluid upwardly, the valve being set to provide the proper back pressure to insure a cushioned stop. The piston is preferably not released until the cage starts on the next revolution and as soon as the pin 42 disengages the lever, the counterweight 45 returns the lever from the position shown in Figure 4 to the position shown in Figure 6. Thus the dump is gently slowed to a stop thereby removing

the shock and jar from the rail aligning lock. The cushion stop may be co-ordinated with the motor controls if desired to become effective at or about the time the cage is decelerated by the previously mentioned operation of switching the drive motor to the low speed windings.

I claim:

1. A car dumper of the character described comprising, a rotatably mounted cage having ring rails at the ends thereof, an approach track leading to the cage, a receiving track leading from the cage, wheels supporting said cage by means of said ring rails, means for driving one of said wheels to rotate said cage and a positive starter for imparting initial movement to said cage including a thrust member rigidly mounted on the side of said wheel and rotatable therewith, a thrust receiving member rotatably mounted on said cage and movable therewith, the axis of the rotatable mounting of said thrust receiving member on said cage being located above and to one side of the point of contact of said thrust member and thrust receiving member when in contact and means for limiting the rotation of the thrust receiving member.

2. A car dumper of the character described comprising, a rotatably mounted cage having ring rails at the ends thereof, an approach track leading to the cage, a receiving track leading from the cage, wheels supporting said cage by means of said ring rails, means for driving one of said wheels to rotate said cage and a positive starter for imparting initial movement to said cage including a thrust member rigidly mounted on the side of said wheel and rotatable therewith, and a thrust receiving member in the form of a lug pivotally mounted on said cage and projecting outwardly therefrom to intersect, when rotating with the cage, the circle of rotation of said thrust member and means for limiting the rotation of the thrust receiving member.

3. A car dumper of the character described comprising, a rotatably mounted cage having ring rails at the ends thereof, an approach track leading to the cage, a receiving track leading from the cage, wheels supporting said cage by means of said ring rails, means for driving one of said wheels to rotate said cage and a positive starter for imparting initial movement to said cage including a thrust member rigidly mounted on the side of said wheel and rotatable therewith, a thrust receiving member in the form of a displaceable lug pivoted on the side of the cage, and a stop member for limiting the angular movement of said thrust receiving member.

4. A car dumper of the character described comprising, a rotatably mounted cage having ring rails at the ends thereof, an approach track leading to said cage, a receiving track leading from said cage, wheels supporting said cage by means of said ring rails, means for driving one of said wheels to rotate said cage and a retarder for checking the momentum of the cage in the final stages of angular movement comprising a vertically positioned hydraulic cylinder having a piston therein, a piston rod, a counterbalanced lever connected to said piston rod, a member attached to and rotatable with said cage to engage said lever and depress said piston to be released therefrom upon commencement of the next revolution of the cage.

GLENN W. MERRITT.
